SUPPORT FOR TOILET TANK REFILL TUBE

Adolf Schoepe, 1620 N. Raymond Ave., Fullerton, Calif.
92631, and Fredric E. Schmuck, 427 Fernhill Lane,
Anaheim, Calif. 92806

Filed Mar. 6, 1972, Ser. No. 232,336

Term of patent 14 years

Int. Cl. D8—08

U.S. Cl. D8—259

Fig. 1.

Fig. 2.

Fig. 3.

Fig. 4.

Fig. 5.

FIG. 1 is a side elevational view of a support for toilet tank refill tube showing our new design;

FIG. 2 is a left end elevational view thereof;

FIG. 3 is a right end elevational view thereof;

FIG. 4 is a top plan view thereof; and

FIG. 5 is a bottom plan view thereof.

The fragmentary broken line representation of a toilet tank and refill tube in FIG. 1 is for purposes of illustration only.

We claim:

The ornamental design for a support for toilet tank refill tube, as shown and described.
